UNITED STATES PATENT OFFICE.

WILLIAM H. VINSON, OF JONESBORO, ARKANSAS.

EXTENSIBLE CAR-STEP.

1,170,368.

Specification of Letters Patent.

Patented Feb. 1, 1916.

Application filed September 13, 1915. Serial No. 50,428.

To all whom it may concern:

Be it known that I, WILLIAM H. VINSON, a citizen of the United States, residing at Jonesboro, in the county of Craighead and 5 State of Arkansas, have invented certain new and useful Improvements in Extensible Car-Steps, of which the following is a specification.

This invention contemplates an improved 10 extensible car step and has as its primary object to provide a step of this character which may be readily applied to steps of railway coaches now in common use, and which will present a neat and attractive appearance.

The invention has as a further object to provide a step which will normally gravitate to operative position and which at the same time may be easily shifted to inoperative 20 position. And a still further object of the invention is to provide an improved step of this character which may be securely locked in inoperative position so that possible accidental injury to the step when not in use, 25 will be reduced to a minimum.

Other and incidental objects will appear as the description proceeds and in the drawings wherein I have illustrated the preferred embodiment of the invention and wherein 30 similar reference characters designate corresponding parts throughout the several views: Figure 1 is a perspective view showing my improved extensible step in connection with the steps of a conventional type of 35 railway coach, Fig. 2 is a rear elevation more particularly showing the mounting of the extensible step, Fig. 3 is a sectional view showing the disposition of the step when moved to inoperative position, and Fig. 4 is 40 a sectional view on a slightly enlarged scale showing one of the anti-friction bearings for the supporting rods of the step.

In illustrating the present invention, I have, for convenience, shown my improved 45 step in connection with steps of a conventional type of railway coach. The steps of the coach, as is usual, are provided with spaced side members 10 and 11 which support the steps proper indicated at 12.

50 In carrying out the present invention, I

employ brackets 13 which are preferably formed from suitable sheet metal and are secured to the inner faces of the members 10 and 11 at oppositely disposed points as more particularly shown in Fig. 2. Formed 55 on the brackets 13 at spaced points, are laterally projecting lugs or guide members 15 which extend inwardly between the members 10 and 11, the brackets being so mounted that the lugs 15 are supported in a plane 60 conforming to the inclination of the steps of the coach.

Mounted to slide upon the lugs 15 of the brackets 13 are supporting rods 16 and 17 respectively which are received within anti-friction bearings carried by the lugs, as more particularly shown in Fig. 4. Preferably, each of these bearings includes an annular sleeve 18 substantially semi-circular in cross-section and in which are arranged 65 a plurality of balls 19 arranged to project through the inner open side of the sleeve to support the rod passing therethrough. In mounting the sleeve 18, each of the lugs 15 is provided with a substantially circular 70 opening into which project equidistantly spaced radial tongues 20, one pair of which is arranged to engage beneath the sleeve, as more particularly shown in Fig. 4, while the other pair is arranged to engage over the 75 sleeve so that the sleeve will be rigidly supported in position. Preferably, the tongues 20 are struck from the lugs and since the brackets 13 are preferably formed from resilient material, the tongues will yieldably 80 engage the sleeves so that any rattling between the parts will be obviated.

At their lower extremities, the rods 16 and 17 are provided with laterally directed terminals extending outwardly beneath the 90 bottom step of the coach and secured to said terminals in any suitable manner is a step 21. The rod 16 at its inner extremity, is bent to provide a substantially U-shaped terminal embracing the rear edge of the side 95 member 11 of the coach steps with the side portion or arm 22 of the said terminal disposed upon the outer side of the said member in substantially parallel relation thereto, while the bight portion 23 of the said ter- 100

rninal is received within a suitable recess formed in the rear edge of the said side member at the upper extremity thereof.

The bight portion 23 of the rod 16 provides a stop while the inner extremity of the rod 17 is bent laterally to form a similar stop 24, the said stops being adapted to engage the uppermost of the lugs 15 of the brackets 13 for limiting the rods 16 and 17 in their downward shifting movement upon said brackets with the step 21 supported in spaced relation below the bottom step of the coach, as illustrated in Fig. 1. In this connection, it will be observed that the step 21 will thus normally gravitate to operative position.

The arm 22 at its free end is bent to provide a lug projecting laterally away from the member 11 of the coach steps and pivotally connected to the said lug is a locking member or lever 25. Arranged to coöperate with the locking member 25 is a post or stop 26 which is mounted to project laterally from the upper extremity of the member 11 of the coach steps and is provided at its outer end with an upstanding stop lug. As particularly shown in Fig. 3, the rods 16 and 17 are shiftable to dispose the step 21 in inoperative position immediately beneath the bottom step of the coach and when so disposed, the locking member 25 may be shifted upon the arm 22 to engage the stop 26 as clearly illustrated in Fig. 2 when the said locking member will then securely support the step 21 in elevated position. Owing to the presence of the upstanding stop lug upon the post 26, the step 21 must first be shifted upwardly above its normal inoperative position in order that the locking member 25 may be swung upon its pivot out of the path of the stop to free the said step. Consequently, accidental displacement of the locking member from the post 26 to release the step 21, will be reduced to a minimum so that when desired, the said step will be safely supported in elevated position.

Having thus described my invention, what I claim and desire to secure by Letters Patent is:

50. 1. The combination with spaced members, of a step mounted to shift thereon to project below the said members, a stop carried by one of said members, and a locking member shiftable with the step and swingingly movable to engage said stop for supporting the step in elevated position.

60. 2. The combination with spaced members, of a step mounted to gravitate thereon to a position projecting below the said members, a pivotally mounted stop carried by one of said members, and a swingingly mounted locking member shiftable with the step and movable into the path of said stop to engage therewith for supporting the step in elevated position.

3. The combination with spaced members, of a step shiftable thereon to project below the members and provided with a supporting rod having an arm embracing one of the members, a stop carried by the said member, and a locking member carried by said arm and shiftable to engage the stop for supporting the step in elevated position.

4. A device of the character described including spaced rods, a step secured thereto, one of said rods being bent to provide a substantially U-shaped terminal, a locking member carried by the said terminal, and a stop for the locking member, the rods being adapted for attachment to spaced members to shift longitudinally thereon with the step projecting below the members and with the said U-shaped terminal embracing the rear edge of one of the members, the stop being supported by the said member and engageable by said locking member for supporting the step in elevated position upon the members.

5. The combination with spaced members, of brackets carried thereby, rods carried by said brackets, a step carried by the rods and shiftable therewith upon the brackets to project below the lower ends of said members, stops carried by the rods and adapted to engage the brackets for limiting the step in its downward shifting movement, a stop carried by one of said members, an arm carried by one of said rods and supported upon the outer side of said member, and a locking member shiftable upon said arm to engage said last mentioned stop for supporting the step in elevated position upon the members.

6. The combination with spaced members, of brackets secured thereto and provided with lugs having openings formed therein, tongues formed from the lugs and projecting into said openings, anti-friction bearings disposed in said openings and engaged by said tongues, rods shiftable through said bearings and provided with a step movable with the rods to project below the lower extremities of said members, a stop carried by one of said members, and a locking member associated with one of said rods and shiftable to engage the stop for supporting the step in elevated position.

7. The combination with spaced members, of rods shiftable thereon and supporting a step movable with the rods to project below the lower extremities of said members, one of the rods being bent to embrace one of the members, a stop carried by said member, and a locking member swingingly connected to the free end of said rod and engageable with said stop for supporting the step in elevated position upon the members.

8. A device of the character described including spaced brackets, anti-friction bearings carried thereby, coacting rods shiftable supported by the said bearings, a step car-

ried by the said rods, a swingingly mounted locking lever carried by one of the rods and shiftable therewith, and a stop associated with said lever, the brackets being adapted for attachment to spaced members with the rods supporting the step projected below the said members and movable to en-

gage the locking member with said stop for supporting the step in elevated position upon the members.

10

In testimony whereof I affix my signature.

WILLIAM H. VINSON. [L.S.]
